US00D893985S

(12) United States Design Patent (10) Patent No.: US D893,985 S
(45) Date of Patent: * Aug. 25, 2020

(54) CARGO HOOK

(71) Applicant: Ronald S. Dankert, Truth or Consequences, NM (US)

(72) Inventor: Ronald S. Dankert, Truth or Consequences, NM (US)

() Term: 15 Years

(21) Appl. No.: 29/687,812

(22) Filed: Apr. 16, 2019

(51) LOC (12) Cl. 08-05

(52) U.S. Cl.

USPC D8/367
